UNITED STATES PATENT OFFICE.

ERNEST ALLEN HUNT, OF MOUNT EDEN, NEAR AUCKLAND, NEW ZEALAND.

VACUUM-CLEANER.

1,136,136.

Specification of Letters Patent.

Patented Apr. 20, 1915.

Application filed November 19, 1913. Serial No. 801,989.

To all whom it may concern:

Be it known that I, ERNEST ALLEN HUNT, a subject of His Majesty the King of the United Kingdom of Great Britain and Ireland, resident of Oakland Road, Mount Eden, near the city of Auckland, in the Provincial District of Auckland and Dominion of New Zealand, have invented new and useful Improvements in Vacuum-Cleaners, of which the following is a specification.

This invention relates to vacuum cleaners used for removing dust and dirt from floors, oilcloth, linoleum, carpets and the like, and it applies especially to the nozzle or part which sits and runs closely on the surface being cleaned and through which the dust and dirt is drawn into the body of the cleaner. This nozzle is adapted to run on a rubber-covered roller situated behind the usual suction opening or slot up through which the dust and dirt is drawn. In front of the suction opening and mounted crossways in the face of the nozzle between the side plates, is a circular bristle brush which is geared so as to be driven from the roller spindle. The bearings of the brush are made adjustable to permit of the pressure of the brush on the floor or the like surface being made light, heavy, or as desired, to suit requirements according to the conditions under which the cleaner is being used.

In the drawings Figure 1 is an end view of the nozzle, Fig. 2 is a cross sectional elevation, Fig. 3 is a bottom plan or face view, Fig. 4 is an end view showing different gearing to Fig. 1, between roller and brush spindles, Fig. 5 shows one of the side plates with slot formed therein and in which work the adjustable brush bearings.

The nozzle A is provided with the usual opening B, and slot C extending the full width of the nozzle, and up through which the dust and dirt is drawn by the vacuum created in the body of the machine. The roller D on which the nozzle A runs is rubber covered and is journaled between the side plates E in the face of the nozzle A at the rear of the slot C, so as to project sufficiently below the plates E to grip the surface on which the cleaner is working. The cylindrical bristle brush F is mounted in the face of the nozzle in vertically adjustable bearings G, so as to be in advance of the slot C. The roller D and brush F are connected by toothed gearing H so that as the nozzle runs on the surface being cleaned, the

brush G is given rotation or caused to revolve. This gearing H can be arranged as shown in Fig. 1 with an even number of wheels to drive the brush in the reverse direction to the roller, or as in Fig. 4 with an odd number of wheels to drive the brush in the same direction as the roller. The gearing H can also be so arranged that the brush may be driven at any suitable speed. The brush bearings G are formed with screws G' thereon which screws extend upward through the front forward portion I of the nozzle one at each side thereof, a milled nut J screwing on to each, the turning of which heightens or lowers the bearings G as desired. The bearings G are guided in their upward and downward movements by slots K in the side plates E, and the nuts J are kept in position by the plates L which are slotted to engage in the grooves J'. The gearing H is incased between one of the side plates E and an outer plate E', fitted thereto, or where the width of the nozzle warrants it, gearing can be used at both sides.

In use and when the nozzle is secured in position on the cleaner the roller D runs on the floor surface and being covered with rubber does not slip or skid or damage the surface being worked on. It also drives or rotates the circular brush F which being situated in front of the slot C stirs up the dust and dirt so that it cannot escape being sucked or drawn by the vacuum up through the slot C and opening B into the machine.

The pressure of the brush F on the surface being cleaned can be regulated by the nuts J and screws G'; this is a special advantage where surfaces with cracks and depressions therein have to be cleaned, as by screwing the brush farther down, it is caused to enter the cracks and depressions and remove all dust and dirt therefrom. Also by using the adjustable bearings described a new brush can be fitted with ease and in a short space of time.

A wall M extends across the front of the nozzle and a partition N is situated just behind the mouth of the slot C to concentrate the effect of the vacuum to the rear of the brush or to the portion of the surface being treated by the brush.

The brush F is of an open bristly nature, allowing the air to pass therethrough thereby keeping it free from clogging and choking by the dust and dirt.

The front L of the nozzle is also provided

with a protecting piece P of rubber or the like to prevent damage being done to furniture or articles with which the cleaner may come in contact.

Having now fully described my invention, what I desire to claim and secure by Letters Patent is:—

A vacuum cleaner comprising a vertical body portion formed with a lower forward projecting portion and a vertical slot extending the full width thereof and opening out of said body portion at the bottom and connecting with a horizontal opening or passage in the back of said body portion near the top thereof, vertical plates secured

to the sides and ends of said body portion, the end plates being provided with vertical slots between the side plates, a roller journaled between said end plates in the rear of said suction slot, adjustable bearings in said slots, a cylindrical brush mounted in said bearings, screw threaded projections on said bearings, extending upward through the lower forward projecting portion of the body and nuts working on said threaded portions.

ERNEST ALLEN HUNT.
